[57] CLAIM

The ornamental design for an earth-retaining module, as shown and described.

DESCRIPTION

FIG. 1 is a perspective view from above of an earth-retaining module showing an embodiment of my new design;

FIG. 2 is a top plan view thereof;

FIG. 3 is a rear plan view thereof;

FIG. 4 is a side elevational view thereof, with the opposite side elevation being a mirror image;

FIG. 5 is a bottom plan view thereof;

FIG. 6 is a front elevational view thereof;

FIG. 7 is a perspective view from above of another embodiment of my new design;

FIG. 8 is a top plan view of my design of FIG. 7;

FIG. 9 is a rear plan view of my design of FIG. 7;

FIG. 10 is a side elevational view of my design of FIG. 7, with the other side being a mirror image;

FIG. 11 is a bottom plan view of my design of FIG. 7; and,

FIG. 12 is a front elevational view of my design of FIG. 7.
